A. Smith, Jr. INVENTOR

UNITED STATES PATENT OFFICE.

ALLEN SMITH, JR., OF THE UNITED STATES ARMY.

HAT-STRAP.

1,269,227.

Specification of Letters Patent. Patented June 11, 1918.

Application filed January 7, 1918. Serial No. 210,593.

To all whom it may concern:

Be it known that I, ALLEN SMITH, Jr., lieutenant colonel in the U. S. Army, a citizen of the United States, whose present address is Camp Lewis, near the city of Tacoma, in the county of Pierce and State of Washington, have invented new and useful Improvements in Hat-Straps, of which the following is a specification.

- 10 My invention pertains to hat straps used to hold the hat securely on the head when the wearer is actively engaged in outdoor life; and the objects of my invention are, first, to provide a hat strap that will hold 15 the hat securely, evenly and comfortably to the front and back of the head alike; second, to provide a hat strap that the wearer can readily attach to the hat and easily adjust the same to fit the head; and 20 third, to provide a hat strap that can be evenly adjusted to each side of the hat without the use of buckles and will hold the hat cord in place.

I attain these objects by means of the device illustrated in the accompanying drawings in which:—

Figure 1 is a side view of a hat with my improved hat strap attached thereto and adjusted to the head, a part of the hat brim 30 being omitted to permit a view of the device.

Fig. 2 is a full size view of the hat strap and lacing cord attachment to the hat, a part of the hat brim being shown in section.

Fig. 3 is a top view of Fig. 1.
35 Similar numerals refer to similar parts in the several views.

Heretofore hat straps have had their ends attached to the hat brim, band or cord at one point only on each side of the hat. 40 With the strap under the back of the head these single points of attachment cause the front of the hat only to be held down securely, while the back of the hat, with a rear wind, will be lifted and cause an uncomfortable sensation of being blown off. 45 If the strap is worn under the chin, the experience will be reversed. The strap thus attached is somewhat crude and has a tendency to injure the hat by pulling it out of shape. The strap has to be provided with a buckle with which to adjust it to the head, and with this means cannot always be done perfectly.

I obviate these several defects by my invention which consists of a single piece of leather strap 1 having its ends provided

with suitable loop-shaped eyelets 2 made flat and elongated to conform with the width of the strap. A lacing string or cord 3 of suitable length provides a means of 60 attaching the strap 1 to the hat 4, and in combination with the loop ends of the strap, forms the basic novelty of my invention.

My invention is especially adapted to military and other hats where a uniform hat 65 cord is commonly used, though it may be used on any form of hat. I have shown it as applied to the ordinary army hat 4 where a military hat cord 5 is used and held together by a front slip knot 6 at its ends. 70

To attach my newly invented hat strap to the hat, I take the lacing string or cord 3, which is made similar to a fine quality of shoe lace with metal end tips, and put one end through the slip knot 6 and draw the 75 center point of the string 3 to the slip knot. Two small holes are then put through the hat brim below the hat cord 5 on each side of the hat, as indicated at 7 and 8 in the several views. These are spaced a suitable 80 distance apart, the space between occupying the center of the sides of the hat.

The left hand end of the string 3 is then put down through the front hole 7 on the left side of the hat, and through the left 85 flat loop eyelet 2 of the strap 1, then up through the rear hole 8, on up back of the military hat cord 5 and then down over the outside of said military hat cord, then backward under the lacing string 3 between the hole 8 and the side of hat 4 and then up over the outside of the lower cord 90 of said military hat cord and finally in between the two cords of the hat cord through a hole punched in the side of the 95 hat as indicated in Fig. 1 and more clearly shown in Fig. 2. The string 1 is now drawn tightly about the military hat cord leaving a loop of suitable length below the hat brim on which the flat loop eyelet 2 can slip and 100 adjust itself. The unused end of the lacing string 3 is smoothly laid in back of the leather sweat band inside of the hat.

The right hand end of the lacing string 3 is then passed to the right side of the hat 105 and attached to the right hand flat loop eyelet of the strap 1 as described for the left side end, and the hat strap is then completely attached for service.

It is to be observed the looping of the 110 lacing string 3 about the military hat cord 5 when drawn tight makes a secure fasten-

2
ing. It can readily be loosened and the loops formed below the hat brim be made the proper length to adjust the strap 1 comfortably to the head. The string loops on each side of the head can be made of equal length by drawing the lacing string 3 to the right or left through the slip knot 6 as may be necessary to evenly adjust them. It will be observed the flat loop eyelets 2 will easily slip on string 3 and so adjust itself that the strain will be equal at holes 7 and 8 and the hat will be held comfortably and evenly on both the front and back of the head at all times.

15 It is to be further observed the passing of the lacing string 3 through the slip knot 6 and fastening its ends to the military hat cord 5 above the rear holes 8 at the sides of the hat securely holds the said military hat cord in place on the hat thus saving the labor of sewing it on.

The flat elongated eyelets 2 can be made by bending a loop on the ends of strap 1, but they are preferably to be made of metal 25 or other hard substance in order that they will easily slip and not bind on the string 3. The strap 1 may be made of two parts fastened together with a buckle, but the adjustable side loops formed by the string 3 30 make a buckle superfluous.

In case my invention is to be attached to a hat without a military hat cord, the string 3 is to be put about the front of the hat and side loops formed below the hat brim as 35 heretofore described and the ends fastened by looping through a multiple of holes near the rear holes 8.

It is to be observed that my invention can be easily attached to a hat by any one. It 40 can also be as readily detached and laid aside for a season when desired.

Having described my invention I claim:—

1. A hat strap having flat metallic eyelets fixed on each end thereof, each of said 45 eyelets attached to the opposite sides of a hat by an adjustable string loop therethrough, each of said loops formed by a

lacing string around the front of said hat and the ends of said string passed through a front and rear hole in the brim on opposite 50 sides of said hat, and each end of said string fastened by passing through a multiple of holes near its respective rear hole in the side brim of said hat.

2. A hat strap having flat eyelets of suitable material fixed on each end thereof, each of said eyelets attached to the opposite sides of a military hat by an adjustable string loop therethrough, each of said loops formed by a lacing string around the front and 60 through the slip knot of the military hat cord of said hat, and the ends of said string passed through a front and rear hole in the brim on opposite sides of said hat, and each end of said string fastened by looping 65 around the said military hat cord, of said hat above said rear holes, and between the cords of said military hat cord to the inside of said hat, all substantially as described and for the purposes set forth.

70 3. A hat strap having flat loop eyelets of suitable material on each end thereof, an adjustable string loop through each of said eyelets, each of said loops attached to the opposite sides of a hat at points in front 75 and back of the center of the sides of said hat, a uniform hat cord on said hat and said uniform hat cord held in place by the lacing string composing said string loops passing around the front of said hat and 80 through the slip knot of said uniform hat cord and said lacing string having its ends securely looped about said uniform hat cord on the opposite sides of said hat as shown and described and for the purposes set forth.

85 4. A hat strap having a flat loop eyelet on each end thereof, each of said eyelets attached to opposite sides of a hat by an adjustable string loop therethrough and the ends of said loops attached to opposite sides 90 of said hat through holes at points in front and back of the center of said opposite sides of said hat.

ALLEN SMITH, JR.
